UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

HOPPER CAR.

Application filed August 31, 1922. Serial No. 585,432.

To all whom it may concern:

Be it known that I, ARGYLE CAMPBELL, a citizen of the United States, residing at Chicago, in the county of Cook and State of Illinois, have invented a certain new and useful Improvement in Hopper Cars, of which the following is a full, clear, concise, and exact description, reference being had to the accompanying drawings, forming a part of this specification.

This invention relates to improvements in hopper cars.

One object of the invention is to provide a hopper car of economical construction and having maximum capacity for given over-all dimensions and large area discharge door openings.

Another object of the invention is to provide a car having hoppers and hopper door arrangements to provide large discharge openings, low center of gravity and with the doors so disposed as to allow them to swing freely without approaching too closely to the rails.

A still further object of the invention is to provide a load-carrying car having a superstructure with an open top so arranged as to obtain additional carrying capacity when the lading is heaped and without exceeding the permissible over-all width of the car.

Other objects of the invention will more clearly appear from the description and claims hereinafter following.

In the drawings forming a part of this specification, Figure 1 is a vertical longitudinal sectional view of a hopper car embodying my improvements, the section being located intermediate the center sill and the side of the car. The end portions of the car, beyond the inner wheels of the trucks, are omitted on account of lack of space but, as will be understood by those skilled in the art, the sloping bottoms are continued upwardly until they meet vertical end walls proper. Figure 2 is a vertical transverse sectional view on the line 2—2 of Figure 1 upon an enlarged scale, parts being broken away in order to accommodate the view on the sheet. Figure 3 is an enlarged vertical transverse sectional view corresponding sub-

stantially to the section line 3—3 of Figure 1, the section extending from one side wall to the center sill, it being understood that the structure will be duplicated on the opposite side of the center sill. Figure 4 illustrates two sectional views, one embodying the side wall top arrangement employed in my invention and the other illustrating the more usual construction, for the purpose of showing the method of obtaining increased capacity when the load is heaped. And Figure 5 is a horizontal sectional view through a portion of the side wall of the car illustrating certain details of construction.

In said drawings, the side walls of the car are indicated broadly by the reference character A; the sloping end bottom walls by the reference character B; and the center sill by the reference character C. As clearly shown in Figure 1, the hopper car is provided with a longitudinal series of four hoppers on each side of the car, the two end hoppers being designated generally by the reference characters D—D and the two intermediate hoppers by the reference characters E—E. Each of said end hoppers D is defined by the lower portion of a sloping bottom sheet B, an inner substantially triangular side hopper sheet 10, an outer inwardly sloping side hopper sheet 11 (see Figure 3), and a transversely extending ridge sheet 12, the latter being secured at its ends to the side sheets 11 and 10 and in part to the ridge plate of the center sill, hereinafter described, and along its upper edge to a vertically disposed transversely extending needle beam 13. Each end wall B is preferably suitably reinforced at its bottom free edge by an angle iron 14, as best shown in Figure 1 and similarly the bottom edges of said ridge sheets 12 are reinforced by angle irons 15 secured to the under sides thereof. By referring to Figure 2, it will be noticed that additional reinforcement is provided at the corners where the transverse ridge sheets unite with the other portions of the car, as by means of corner castings 16. For a more detailed description of this type of corner bracing, reference may be had to my pending application, Serial No. 521,292,

2
filed Dec. 10, 1921. To each transverse ridge sheet 12 is pivotally attached, along its upper edge, a transversely extending end hopper door 17. Preferably, each pair of transversely alined end hopper doors 17 is rigidly connected by suitable bracing as indicated at 18 so that the same may be operated simultaneously by means of suitable door operating mechanism actuated from the corresponding adjacent shaft 19. It will be noted that the doors 17, when in closed position, extend approximately at right angles to the planes of the sloping bottom walls B.

At the center of the car, a transversely extending vertical partition sheet 20 is employed, the latter also serving in the nature of a needle beam and suitably reinforced along its bottom edge by angle iron 21 and tie plate 22, the needle beam plates 13 being similarly reinforced along their bottom edges, as clearly shown in Figure 1. To the opposite sides of the partition sheet 20 on each side of the center sill are secured oppositely downwardly sloping ridge sheets 23—23, the latter being suitably reinforced along their bottom edges by angle irons 24—24. Also secured to the faces of the needle beam plates 13 which face toward the transverse center of the car, are other ridge sheets 23—23, similarly reinforced along their bottom edges.

By reference to Figure 1 of the drawings, it will be noted that all of the ridge sheets 12 and 23, have their top edges located in a plane intermediate the top and bottom of the center sill construction. It will further be observed that the ridge sheets 12 are appreciably narrower than the ridge sheets 23 and slope from the vertical at an appreciably blunter angle than do the other ridge sheets 23—23 which are employed in defining the intermediate hoppers E so that the lower edges of the ridge sheets 23 terminate at lower points than do the lower edges of the ridge sheets 12. Secured to the lower edge of each intermediate hopper ridge sheet 23 and within the corresponding angle iron 24, is a hopper door 25, there being a pair of said doors 25 for each intermediate hopper E and said doors meet approximately horizontally when in closed position, as shown in Figure 1. Each transversely alined pair of doors 25 is also preferably operated simultaneously by rigidly uniting them by a suitable cross brace 26. All four doors of the transversely alined pair of hoppers E to the right of the center partition 20, are preferably operated from a transversely extending shaft 27 by a suitable chain, sheave wheel and link connections, not shown, but which are located within the center sill construction. The other set of four doors for the intermediate hoppers E are similarly operated from a shaft 27 shown in section in Figure 1.

Referring to Figure 1, the top of the rail is indicated by the line 28 and it will be noted that the end hopper doors and the intermediate hopper doors 25, when swung to open position, will all clear the rail at approximately the same height, this result being brought about by the fact that the intermediate hopper doors 25, although hinged about lower points than the end hopper doors 17, are made narrower. At this point, it will be observed that, by sloping the intermediate ridge sheets 23 at the acute angles shown and extending them downwardly to the low point indicated and by employing substantially horizontal doors 25, I obtain unusually large capacity in the bottoms of the hoppers E and also thereby lower the center of gravity of the load. With my arrangement of two end hoppers and two intermediate hoppers on each side of the center sill in a longitudinal series, as shown, I am enabled to obtain a carrying capacity of a normal load of seventy tons in a car having an over-all length of 40' 5" between striking plates and an over-all width of 10' 1" from side to side and, at the same time, obtain large areas for discharging the load.

The center sill construction C of the car, is best illustrated in Figures 1 and 2, where it will be noted that I employ two specially rolled beams 29—29, each of which has a main vertically extending web 30, a top inwardly extended flange 31, and bottom outwardly and inwardly extended flanges 32—32. By this arrangement, I am enabled to obtain great strength in those portions of the beams 29 which are subject to tension without unduly extending the over-all width of the center sill at the top. Surmounting and secured to the beams 29 of the center sill construction, is a ridge plate 33 of substantially inverted V shape which extends from one end or bottom wall B to the other, as shown in Figure 1. The beams 29, from the bottom walls B to the ends of the car, are preferably covered by a flat plate 34, as best shown in Figure 1.

Referring now more particularly to Figures 3, 4 and 5, the side wall structure of the car is made as follows. A plurality of vertically extending inside stakes 35 are employed, said stakes being preferably in the form of angles. Applied to the outer faces of the stakes 35 are sheet metal plates 36, the joints of said plates 36 being covered by narrow plates 37 so that the exterior of the side walls of the car presents a substantially flat unbroken surface and in this connection it will be understood that the side wall plates are spaced apart the maximum permissible distance allowed in service. Along their top edges, the side wall plates 36 are bent inwardly and upwardly at an angle of approximately 45° as shown at 38 in Figure 1.

3. Secured to the side plates along their inwardly bent upper edges 38, are bulb angles 39, each having a flange 40 thereof riveted to the under side of the inturned edge 38 of the corresponding side wall and with the other flange 41 thereof sloping upwardly and outwardly at approximately 45°.

By referring to Figure 4 and comparing the views *a* and *b*, it will be seen that I obtain an increased capacity when the load is heaped as indicated by the shaded area *x* in view *a*, as compared with previous constructions, even when inside stakes have been employed. This is due to the fact that I arrange the bulb angles 39 as shown so that the flanges 41 thereof provide proper retaining means for the load up to the top edges of the bulb angles. By employing bulb angles and locating the bulb proper at the points shown, I obtain the necessary rigidity for the load-retaining portions of the bulb angles 39.

I have herein shown and described what I now consider the preferred manner of carrying out the invention, but the same is merely illustrative and I contemplate all changes and modifications that come within the scope of the claims appended hereto.

I claim:

30 1. A hopper car having sloping end floors and eight discharge hoppers arranged in two longitudinal series of four each on each side of the center sill, each of said series including two end hoppers and two intermediate hoppers, each said end hopper being defined by side hopper sheets, a sloping end floor and a transverse ridge sheet, and each of said intermediate hoppers, being defined by side hopper sheets and two oppositely extending transverse ridge sheets, said transverse ridge sheets of the intermediate hoppers sloping downwardly at a more acute angle and to a lower point than said transverse ridge sheets of the end hoppers; and a transversely extending hopper door hinged to the lower edge of each said transverse ridge sheets, the end hopper doors being of greater length than the intermediate hopper doors.

50 2. A hopper car having sloping end floors and four hoppers on each side of the center sill, the car having three transversely extending ridges of inverted approximately V shape, located intermediate said end floors, the two end ridges each comprising a sheet nearest the end floor which slopes downwardly at one angle, all the remaining ridge sheets sloping downwardly at a more acute angle and to a point nearer the rail than said end ridge sheets; and a hopper door hinged to each of said ridge sheets.

65 3. A hopper car having sloping end floors and four hoppers on each side of the center sill, the car having three transversely extending ridges of inverted approximately

V shape located intermediate said end floors, the two end ridges each comprising a sheet nearest the end floor which slopes downwardly at one angle, all the remaining ridge sheets sloping downwardly at a more acute 70 angle and to a point nearer the rail than said end ridge sheets; a hopper door hinged to each of said ridge sheets; and a center sill having a ridge top plate, said transverse ridges having their tops located below the 75 top of the ridge of the center sill.

4. A hopper car having sloping end floors and four hoppers on each side of the center sill, said car having three transversely extending vertical plates located intermediate 80 said end floors on each side of the center sill; a pair of transversely extending ridge sheets secured to each of said vertical plates, one on each side thereof, the transverse ridge sheets on the sides of said vertical plates 85 nearest the ends of the car being narrower than and sloping downwardly at a more obtuse angle than the remaining transverse ridge sheets; and a hopper door hinged to the lower edge of each ridge sheet, the end 90 hopper doors cooperating with the end floors to close the discharge openings of the end hoppers, and the other doors of the intermediate hoppers having their free edges meeting when in closed position. 95

5. A hopper car having sloping end floors and four hoppers on each side of the center sill, the car having three transversely extending ridges of inverted approximately V shape located intermediate said end floors, 100 the two end ridges each comprising a sheet nearest the end floor which slopes downwardly at one angle, all the remaining ridge sheets sloping downwardly at a more acute angle and to a point nearer the rail than 105 said end ridge sheets; and a hopper door hinged to each of said ridge sheets, the hopper doors for the end hoppers extending approximately at right angles to the end floors when in closed position, and the hopper 110 doors for the intermediate hoppers extending approximately horizontally when in closed position.

6. A dump car having end and side walls, 115 said side walls each including: side wall sheets and stakes on the inner faces thereof, the top edges of said side wall sheets being sloped inwardly and upwardly; and longitudinally extending angle irons secured to said inwardly sloping top edges of the side 120 wall sheets, the lower flanges of the angle irons being secured to said inwardly sloping edges and the other flanges of the angle irons sloping upwardly and outwardly whereby to obtain increased load-carrying 125 capacity.

7. A dump car having end and side walls, 130 each of said side walls including: side wall sheets and stakes on the inner faces thereof, the top edges of said sheets being bent in-

wardly and upwardly; and a top rail bulb angle secured to said inwardly bent top edges of the side sheets, the upper flange of the bulb angle sloping upwardly and outwardly approximately 45° whereby to obtain increased load-carrying capacity for the car.

In witness that I claim the foregoing I have hereunto subscribed my name this 9th day of August 1922.

ARGYLE CAMPBELL.
